Primary Examiner — T Chase Nelson*Assistant Examiner* — Jonathan J Han(74) *Attorney, Agent, or Firm* — Quarles & Brady LLP(57) **CLAIM**

The ornamental design for a vehicle cover, as shown and described.

DESCRIPTION

FIG. 1 is a top, right, and front isometric view of the ornamental design for a vehicle cover;

FIG. 2 is a right side elevational view of the vehicle cover of FIG. 1;

FIG. 3 is a front elevational view of the vehicle cover of FIG. 1; and,

FIG. 4 is a top plan view of the vehicle cover of FIG. 1. The dash-dash-dash lines are included for the purpose of illustrating portions of the vehicle cover that form no part of the claimed design. The dash-dot-dash broken lines depict boundary lines and form no part of the claimed design.

1 Claim, 4 Drawing Sheets
